UNITED STATES PATENT OFFICE

2,229,787

HOLDER FOR COILS OF METAL WIRE OR STRAPPING

Geoffrey Joseph Abbott, Carshalton, England, assignor to Packers Supply Company Limited, Surrey, England, a company of Great Britain

Application April 7, 1939, Serial No. 266,668
In Great Britain December 19, 1938

10 Claims. (Cl. 242—90)

This invention relates to an improved holder for supporting coils of wire or metal strapping of the kind used for example in binding cases, bales, boxes and the like, and the primary object of the invention is to provide a support which will enable the coil to be rotated and the wire or strapping drawn off from the coil by simply pulling on the free end of the wire or strapping.

In accordance with the invention there is provided an improved holder for a coil of wire or metal strapping comprising a support, a carrier mounted for rotation on said support, and on which a coil may be rested in substantially coaxial relationship therewith and a guide through which the wire or strapping is passed as it is drawn off the coil. This guide, which may be conveniently formed as a tube, may be shaped and mounted so as to lead the wire or strapping as it is drawn off from the coil in a direction at an angle to the plane of rotation of the carrier.

Thus for example the rotary carrier with a coil thereon may be arranged close to the floor and the wire or strapping as it is drawn off the coil may be directed upwards by the guide towards the work level.

In accordance with the invention, the guide for the wire or strapping may also be mounted so as to be capable of limited movement on the support and the entry end of the guide arranged to engage in one of its positions with a part on the rotary carrier so as to prevent the latter rotating. The shape of the guide may be such that a pull upon the wire or strapping passed through the guide, to unwind the coil, effects such a movement of the guide as will disengage its entry end from the part on the rotary carrier, so that the latter is made free to rotate. Biasing means such as a spring may be provided to effect a return movement of the guide to the stopping position when the pull on the wire or strapping is released.

The means provided on the carrier for co-operation in the above described manner with the entry end of the guide to stop rotation of the carrier, may comprise a number of upward projections near the periphery of the carrier which also serve to limit the expansion or degree of uncoiling of the coil on the carrier due to the inherent springiness of the material. In the position of rest the entry end of the guide lies in the path of rotation of said projections and forms a stop for engagement by any one of them, whilst during the operation of drawing off the wire or strapping from the coil said guide is moved by the tension of the wire or strapping and the entry end of the guide moved from the path of the projections and

to a position nearer the axis of the rotary carrier.

Whilst the improved holder is adapted for use with coils of wire or with ribbon wound coils of strapping, it offers particularly marked advantage when used in the manipulation of mill wound coils of strapping, that is to say coils in which each of the superposed layers in the coil includes a plurality of convolutions after the manner of the threads wound upon a bobbin. Such mill wound coils of strapping are of much greater weight than ribbon wound coils of similar diameter.

With a view to still further facilitating the handling of such heavy mill wound coils, the improved holder according to the invention may be mounted upon wheels so as to be readily transportable.

The invention is illustrated by way of example in the accompanying drawings in which

Fig. 1 is a view in perspective of a complete coil holder according to the invention.

Fig. 2 is an end elevation looking from the left in Fig. 1 and with a mill wound coil of metal strapping shown in position.

Fig. 3 is a view in plan of the holder with a coil of strapping in position.

Referring to the drawings, a support of metal tubular construction comprises a main tube 1 and a cross tube 2 at one end of said main tube 1, this cross tube housing an axle for a pair of wheels 3. At the other end of the main tube 1 is affixed a further tube 4 which extends upwardly from tube 1 and is bent to form a convenient handle 5. A foot 6 is provided at the junction of tubes 1 and 4 which when rested upon the floor supports bar 1 substantially horizontally.

At a point intermediate the length of tube 1 is fixedly mounted an upwardly extending pillar 7 shown in dotted lines in Fig. 1 and having a conical tip.

The rotary coil carrier is formed by a spider having four symmetrically arranged arms 8 extending radially from a central hub sleeve 9 closed at its upper end and adapted to fit over and rotate upon the pillar 7.

A screw 10 passed through a hole in the end of the hub sleeve 9 and into the end of the pillar 7 serves to retain the carrier on the pillar.

Bracing webs 11 are provided between the arms 8 and the hub sleeve 9, these webs 11 being of a radial length somewhat less than the radius of the space within a coil of wire or strapping 12 to be used (see Fig. 3). The upper outer corners 13 of the webs 11 are preferably chamfered to facilitate the placing of a coil in position on the carrier.

Upon the extremities of the arms 8 of the carrier are fixed metal angle pieces 14 one arm 15 of each of which extends upwards from the arms 8, at a radial distance from the pillar 7 which is substantially greater than the external diameter of a full and unloosened coil of strapping or wire (see Fig. 3). In some cases the angle pieces 14 may be adjustable on the arms 8 of the carrier so that this radial distance may be varied.

10 The guide for the wire or strapping as it is drawn off the coil 12 is in the case illustrated formed of a shaped tube 16 of an internal diameter somewhat greater than the width of the widest strapping to be handled, and is curved as shown 15 so that when mounted a part near its entry end may lie substantially parallel to the outer turns of a coil of strapping on the carrier and inwards with regard to the path of rotation of the upwardly extending limbs 15 of the angle pieces 14 on the carrier arms 8, and at a level convenient for the entry of the strapping from the coil 12 without kinking it, as shown for example in Fig. 2. The guide tube 16 may be conveniently mounted on the upwardly extending tube 4 forming part 20 of the support for the carrier, and the entry end 16' of the tube directed substantially tangentially of the circular path of rotation of projections 15 as shown in Fig. 3. The tube 16 is also shaped and mounted so as to have an upward sweep from 25 its inlet end 16' to its outlet end 16'', Fig. 2.

In use, the coil of wire or strapping 12 having been placed in position on the carrier by passing it over the webs 11, the free end of the coil is threaded through the guide tube 16.

30 The holder may now be brought to a suitable position on the floor relatively to the work bench by means of the wheeled support 1, 2, 3, and handle 5, and thereafter material may be drawn off as required from the coil 12 by pulling it 35 through the guide tube 16, the coil and carrier meanwhile rotating on the bearing pillar 7.

In the case of flat metal strapping, the strapping cannot of course bend in its own plane as it is drawn off the coil 12, but the tubular form 45 of the upwardly swept guide 16 permits a progressive twisting of the strapping as shown in Figs. 2 and 3, and thus it may be drawn upwards from the coil near the floor to a higher working level.

50 In section, strapping within the guide tube 16 forms a chord with the internal surface of said tube, but it is the edges of the inner side only of the strapping, that is to say the edges of the surface originally towards the centre of the coil 12, which make rubbing engagement with the interior of the tube 16. Thus the improved holder is without adverse effect upon lacquering, printing or the like on the outer surface or edges 55 of treated strapping.

60 The direction of the twist imparted to strapping in the guide tube 16 in the case illustrated is such as to bring the inner side of the strapping uppermost, but a twist in the reverse direction to bring the outside of the portion of strapping about to be used uppermost, can readily be imparted by hand by the operator.

65 Alternatively a ring 22 may be provided on the tube 4 in a position above the outlet end of guide tube 16, through which the strapping may be passed after leaving the end of tube 16 and the reversal of the strapping effected by pulling it in an appropriate direction away from the ring 22.

The ends 16' and 16'' of the guide tube 16 may 70 with advantage be flared.

The extent to which the coil on the carrier may expand or unwind is limited as clearly shown in Fig. 3 by the upwardly extending limbs 15 of the angle pieces 14 on the carrier arms 8.

75 The guide tube 16 may also be utilised to bring the rotary carrier to a standstill when the pull on the wire or strapping passing therethrough is relaxed. For this purpose the guide tube 16 is mounted by clamping it fixedly intermediate its length by means of a stirrup 17, to a bracket 10 member 18 formed of sheet metal bent to the shape shown and mounted for limited angular rocking movements on the straight portion of tube 4.

At the lower end of bracket member 18 is provided an extension piece 19 extending towards the rotary carrier and having a downwardly extending fork 20 at the free end thereof, which fork embraces the tube 1. A spring 21 affixed to tube 1 extends through the fork 20 to urge the 20 bracket 18 and tubular guide 16 in a clockwise direction in Fig. 3 about the axis of tube 4.

The dimensions of the fork 20 are such that the bracket 18 and guide tube 16 may move between two positions in one of which the entry end 16' of the guide tube lies in the path of rotation of projections 15 on the rotary carrier as shown in full lines in Fig. 3 and a position where the entry end 16' of said tube 16 lies at the side 30 of said path towards the axis of the rotary carrier as shown in dotted lines in Fig. 3, in which position the projections 15 can pass, during rotation of the carrier, outside the lower part of the tubular guide.

The pull upon the strapping extending through the guide tube 16 causes the bracket 18 and tube 16 to move against spring 21 into the dotted line position of Fig. 3 towards the coil 12 and out of the path of projections 15, so that the rotary carrier is free to rotate and the coil to unwind. 40

If the strapping is passed through the ring 22 as described above, the tube 16 will still be rocked in this manner when the strapping is pulled, irrespective of the direction in which the strapping is pulled away from said ring. 45

When the pull on the strapping is relaxed, the bracket 18 and tubular guide 16 are returned by spring 21 to the full line position of Fig. 3 where the first following projection 15 abuts against the end 16' of the tubular guide to bring the rotating carrier to a standstill. 50

I claim:

1. An improved holder for a coil of wire or metal strapping, comprising a support, a rotary carrier mounted on said support and on which a coil may be rested in substantially co-axial relationship therewith, a projection adjacent the periphery of said rotary carrier and a shaped guide through which the material is passed as it is drawn off the coil and adapted to lead the material in a direction at an angle to the plane of rotation of the carrier, said shaped guide being mounted with limited movement upon the support and means to limit the movement of said guide so that the entry end thereof may be moved between a position in the path of the projection on the rotary carrier and a position out of said path and nearer the axis of the carrier. 60

2. An improved holder for a coil of wire or metal strapping, comprising a support, a rotary carrier mounted on said support and on which a coil may be rested bodily in substantially co-axial relationship therewith, a projection on said rotary carrier, a tubular guide through which 70

the material is passed as it is drawn off the coil, said guide being adapted to lead the material in a direction at an angle to the plane of rotation of the rotary carrier and being mounted so as to be capable of limited movement upon the support so that the entry end thereof may be moved into and out of the path of rotation of the projection on the rotary carrier and biasing means adapted to urge the entry end of said guide member into 10 the path of rotation of the projection.

3. An improved holder for a coil of wire or metal strapping comprising a transportable support, a rotary carrier mounted on said support and on which a coil may be rested bodily in substantially co-axial relation therewith, said carrier including a rotary hub, a series of radial arms connected with said hub and projections adjacent the outer ends of said arms adapted to limit the expansion of a coil in position on the carrier, 20 a curved tubular guide through which the material is passed as it is drawn off the coil, said guide being mounted with limited movement on the support so that the inlet end thereof is capable of movement between a position in the path of rotation of the projections and a position on the inside of said path, and disposed so as to lead the material spirally upwards and outwards across the path of rotation of said projections.

4. An improved holder for a coil of wire or metal strapping comprising a transportable support including an upwardly directed column, a rotary carrier mounted on said support and on which a coil may be rested bodily in substantially co-axial relation therewith, said carrier including 25 a hub, a series of radial arms connected with said hub, upwardly extending webs on the inner ends of the arms adapted to enter the central space of a coil to locate the latter on the carrier and projections adjacent the outer ends of said arms 40 adapted to limit the expansion of a coil in position on the carrier, a tubular guide through which the material is passed as it is drawn off the coil, said guide being pivotally mounted for limited rocking movements on the column on the support so that one end thereof may engage and disengage a projection on the rotary carrier and being disposed so as to lead the material from the coil in a direction at an angle to the plane of rotation of the rotary carrier and outwardly 45 across the path of rotation of the projections adjacent the outer ends of the arms.

5. An improved holder for a coil of wire or metal strapping, comprising a support, a rotary coil carrier mounted on said support and on which a wound coil may be placed bodily in substantially co-axial relationship therewith, means adjacent the periphery of the rotary carrier to limit the unwinding of the coil on the carrier, and a shaped tubular guide of compound curvature through which the strip material is passed as it is drawn off the coil, said guide being mounted on the support with its inlet end projecting on the inner side of the path of rotation of the means for limiting the unwinding of the coil and disposed so as to direct the unwound material in an upward curve from the plane of rotation of the rotary carrier and in a curve outwards across the periphery of the rotary carrier at an inclination to the plane of rotation of the rotary carrier.

6. An improved holder for a coil of wire or metal strapping, comprising a support, a rotary coil carrier mounted on said support and on which a wound coil may be placed bodily in substantially co-axial relationship therewith, means adjacent the periphery of the rotary carrier to

limit the unwinding of the coil on the carrier, and a tubular guide of smooth compound curvature through which the strip material is passed as it is drawn off the coil, said guide being mounted on the support with its inlet end projecting on the inner side and substantially tangentially of the path of rotation of the means for limiting the unwinding of the coil and disposed so as to direct the unwound material in an upward curve from the plane of rotation of the rotary carrier and in a curve outwards across the periphery of the rotary carrier at an inclination to the plane of rotation of the rotary carrier.

7. An improved holder for a coil of wire or metal strapping, comprising a support, a rotary carrier mounted on said support and on which a coil may be rested bodily in substantially co-axial relationship therewith, a projection adjacent the periphery of said rotary carrier, a curved tubular guide through which the material is passed as it is drawn off the coil and adapted to lead the material in a direction at an angle to the plane of rotation of the carrier, said guide being mounted with limited movement upon the support, means to limit the movement of said guide so that the entry end thereof may be moved between a position in the path of the projection on the rotary carrier and a position out of said path and nearer the axis of the carrier, and biasing means adapted to urge the entry end of said 30 guide into the path of rotation of the projection.

8. An improved holder for a coil of wire or metal strapping comprising a support, a rotary carrier mounted on said support and on which a coil may be rested bodily in substantially co-axial relationship therewith, a projection on said rotary carrier, and a curved tubular guide through which the material is passed as it is drawn off the coil, said guide being mounted so as to be capable of limited movement on the support about an axis parallel to the axis of rotation of the rotary carrier and so that the entry end thereof may be moved into and out of the path of rotation of the projection on the rotary carrier, and biasing means adapted to move the 40 guide in the direction to locate the entry end in the path of the projection on the rotary carrier and adapted to be overcome to permit the said entry end to move from said path when a pull is exerted on the material.

9. An improved holder for a coil of wire or metal strapping, comprising a support, wheels on said support to render said support transportable, a rotary carrier mounted on said support and on which a coil may be rested bodily in substantially co-axial relationship therewith, projections on the rotary carrier adjacent the periphery thereof and projecting parallel to the axis of rotation of the carrier, and a tubular guide through which the material is passed as it is drawn off the coil, said guide being mounted for limited rocking movement on the support so that the inlet end thereof may be moved into and out of abutting engagement with a part of the rotary carrier, said guide being adapted to 50 direct the material from the coil in a direction at an angle to the plane of rotation of the carrier and outwards across the path of rotation of the projections.

10. An improved holder for a coil of wire or metal strapping, comprising a support, a rotary carrier mounted on said support, a plurality of symmetrically arranged projections adjacent to the periphery of, and extending in a direction normal to the plane of rotation of said carrier 70

and adapted to limit the expansion of a coil of material placed on said carrier in substantially co-axial relationship therewith, and a tubular guide member mounted with limited movement on the support and through which guide tube the material is passed as it is drawn off the coil, the entry end of said movable guide tube being arranged to move between a position where it lies

in the path of rotation of the projections on the carrier and a position where it lies close to and inside the path of rotation of the projections on the carrier, and the outlet of said guide tube being directed upwardly and outwardly relatively to the plane of rotation of the carrier. 5

GEOFFREY JOSEPH ABBOTT.
